CONCRETE WINDOW TRIM AND METHOD
OF MAKING

Everett Grey Livesay, Miami, Fla.

Application October 7, 1937, Serial No. 167,839

4 Claims. (Cl. 72—98)

The invention, generally considered, relates to a precast concrete window trim or frame, or the like, and also to the method of making same.

One of the objects of my invention is to provide 5 a precast concrete trim adapted for use with structures formed of poured concrete or concrete blocks, said trim being so formed as to provide a bond therebetween and the adjacent wall structure.

10 Another object of the invention is to provide a trim formed integrally with inwardly projecting shoulders and provided adjacent thereto with metallic means to which there may be secured a metallic window frame, the latter being adapted 15 to abut against said shoulder.

Still another object of my invention is to provide a trim so formed and constructed that it may be placed in position in such manner as to afford surfaces adjacent the corresponding wall 20 surfaces so that both the inner and outer wall facings may be joined to said trim in a simple and inexpensive manner.

A still further object of the invention is to provide a unit structure to which may be readily attached 25 a window frame and Venetian blinds by the ordinary mechanic without the use of tools other than a screw driver.

A more specific object is to provide a pre-cast one-piece concrete window trim which may be 30 made in various sizes and different widths to accord with the thickness of the wall structure and which may be disposed with its front and rear surfaces or edges in different relative positions with respect to the outer and inner wall surfaces 35 depending upon the preference of the architect or builder.

Another detailed object of the invention is to provide a unitary pre-cast concrete window trim of such construction and so related to the adjacent 40 wall structure and to the metallic window frame anchored thereto and having other characteristics which will render the entire construction weatherproof by the avoidance of exposed joints.

45 An additional object is to provide such a window trim which will be simple and easy to pre-cast and install, permanent in its nature, subject neither to shrinkage nor warping, and which will in every respect be a distinct improvement in 50 the art.

To the attainment of the foregoing and other objects and advantages, the invention preferably consists in the details of construction and the arrangement and combination of parts to be hereinafter more fully described and claimed, and

illustrated in the accompanying drawings in which:

Figure 1 is a front elevation of a complete double casement window structure embodying my invention, 5

Figure 2 is a vertical longitudinal section therethrough,

Figure 3 is a horizontal sectional view taken along the line 3—3 of Figure 2 through but one side of the trim and showing the metallic frame 10 and sash construction in detail,

Figure 4 is a sectional perspective view of the trim and blind guides with the metal frame and sash omitted,

Figure 5 is a horizontal sectional view through 15 the trim structure for a single window though not limited to such, this view corresponding essentially to Figures 3 and 4,

Figures 6, 7 and 8 are horizontal sectional views similar to Figure 5 but showing variations in the 20 location of the trim with respect to the wall and the finishing stucco and plaster,

Figure 9 is a fragmentary inside face view of the upper portion of one of the trim sides,

Figure 10 is a longitudinal sectional view 25 therethrough on substantially the line 10—10 of Figure 9,

Figure 11 is a detail cross sectional view taken on the line 11—11 of Figure 10,

Figure 12 is a vertical cross sectional view illustrating a portion of the molds for casting the trim, 30

Referring more particularly to the drawings, I have in every instance disclosed the trim as a pre-cast structure including a lintel 15, sides 16, 35 and a sill 17 regardless of whether the trim be designed for the installation of single or double casement windows and likewise regardless of whether the trim is to be mounted within openings in a poured concrete wall W or within openings in a wall B of hollow block construction. 40

As mentioned above, the trim is pre-cast in an appropriate mold shown in Figure 12 and to be described hereinafter, the formation being such as to define longitudinally extending recesses 18 45 in the outer surfaces of the lintel 15 and sides 16, so as to provide means for locking or bonding the structure within a window opening in a wall as it is poured, in the case of a solid wall construction W or by pouring in concrete locks or bonds 50 19 in the case of a hollow block construction B such as is illustrated in Figure 5. The sills need not have any such recesses at the underside particularly for the reason that filling them with concrete would be difficult and for the additional 55

reason that they are unnecessary in view of their presence in the lintel and sides. Extending substantially centrally of the lintel, sides and sill is a continuous ridge 28 shaped to define an abutment shoulder 21 at its outer side, that is to say, toward the outside of the building. The other edge 22 need not be formed as a square shoulder. From the ridge on the underside of the lintel to the edges of the trim the surfaces 22 and 23 are 10 upwardly inclined, and from the opposite edges of the ridges on the sides the surfaces are inclined in opposite directions, as shown at 24 and 25. Similarly the top surface of the sill is inclined in opposite directions from the ridge thereon, as shown at 26 and 27. The purpose of these various inclined surfaces is to give a proper taper to the trim so that it will draw from the mold when cast.

The undersurface of the outer edge portion of 20 the sill is formed with a longitudinally extending recess 28 defining a drip and similarly the underside of the outer edge portion of the lintel is preferably recessed at 29 to define a drip. Quite naturally the provision of these drips improves 25 the weatherproof qualities of the construction.

In the form of trim shown in Figures 2, 3, 4 and 5 the lintel, sides and sill are grooved at their outer and inner edges to define shoulders 30, against which the outside stucco and the inside 30 finishing material may abut so as to overlap the joint between the trim and the concrete of the building wall, thereby excluding rain. The exterior stucco is represented in the figures mentioned at 31 while the inside finishing laths and 35 plaster, plaster board or the like is represented at 32, it being customary to secure the interior finish to furring strips 33 appropriately anchored to the wall.

Another feature it is well to mention is that 40 the entire trim is reinforced, preferably by galvanized steel rods 34 as is common in concrete construction. Likewise, it may be well to dispose a reinforcing wire screen 35 between the building wall and the exterior stucco, this screen extending into or being embedded within the trim 45 when it is cast, as shown in Figure 3. However, for facility of construction and to reduce cost and labor, it is conceivable that this might be omitted.

It should be mentioned that the only differences between what is shown in Figures 6, 7 and 8 from what has been above described, are different positions of the trim with respect to the wall faces and different locations of the 50 stucco and finishing plaster with respect to the trim, it being observed that in these figures there are no shoulders such as shown at 30 in Figures 2, 3, 4 and 5. In Figure 6 the outer edge or face of the trim is flush with the wall while the inner edge or face projects inwardly beyond it and the stucco and the plaster board or the like simply 55 slightly overlap the joint between the trim and the wall structure. In Figure 7 the inner edge or face of the trim is flush with the wall while the outer edge or face projects beyond it and the stucco abuts the trim while the finishing plaster or its equivalent overlaps the joint and is extended inwardly at right angles so that its edge abuts the edge of the trim at the inside of the 60 building. In Figure 8 the trim is arranged as in Figure 6 and the plaster board or its equivalent overlaps the trim joint with the wall at the inside of the building, while the stucco is continued clear across the outside face or edge of the trim. 65

Possibly other minor variations might be resorted

to depending upon the preference or taste of the architect or builder. However, it is thought sufficient for all reasonable purposes to indicate just these few modifications.

When the trim is being cast there is embedded 5 in the ribs or ridges 28 a series of L-shaped metallic members 36 which have their outer ends flush with the surfaces of the ridges and which have their outer ends formed with threaded sockets 37, as shown most clearly in Figure 3. 10

It is a distinct feature of the invention that while a wooden construction could be used, I prefer to employ metallic window frames and sashes therewith. I therefore provide a frame constructed of substantially Z-shaped metallic frame bars 38 located at the inner faces of the ribs or ridges 28 and extending over the shoulders 21, it being probably preferable to interpose some appropriate packing 39 between the frame bars and the concrete of the trim to provide 15 weatherproof joints. These frame bars are secured to the trim by screws 40 which pass through the frame bars and the packing and into the threaded sockets 37. By this means the metal frame is effectually anchored to the trim. 20

The sashes employed may be single or double casements and are also preferably of metal and formed of substantially Z-shaped bars 41 located inwardly of the confines of the frame 38 but having flanges abutting against the forward or outer and also the rear flanges of the frame bars 38 so as to limit inward swinging movement of the sash or sashes as the case may be. The glass 42 is mounted within the sash frame 41 and may be putted or otherwise packed, as shown at 35 43, in any ordinary or preferred manner. It will be noted that when the sash is closed access cannot be had to the screws 40 so that protection is had against a marauder seeking to remove the 40 frame.

In many localities it is quite the practice to equip windows with Venetian blinds and in order that my trim may accommodate them, channel members 44 are embedded in the confronting faces of the sides. These channel members have 45 lateral flanges 45 extending toward each other to define slots 46 having flaring entrances 47 at the top. The back of each channel member is formed with an upstanding prolongation or flange 48 shown by dotted lines in Figure 9 for a 50 purpose to be described. Embedded within each side member of the trim in spaced relation above the channel 44 is a U-shaped anchor member 49 having its ends provided with lateral wings 50 so as to prevent any possibility of withdrawal if 55 subjected to strain. Secured to each anchor member 49 is a bracket 51 having its lower end formed with a curved bearing or cradle 52.

The Venetian blind itself is shown in its contracted or uppermost position at 53 in Figure 2 60 and is of the customary construction. The upper rail of such a blind, which rail is indicated at 54 in Figures 9, 10 and 11, has its ends engaged upon the cradle or bearing members 52 at the opposite sides of the trim. The lower rail or bar 65 55 of the blind structure is shown equipped with a stem 56 adapted to slide along the slot 46 and terminating in an enlarged head 57 located within the channel 44.

As mentioned above, each channel member is 70 formed at its upper edge with the flange 48 which extends upwardly so as to permit the head 57 to be inserted within the open top of the channel subsequently to which the mechanic, by means of a screw driver or the like, simply bends or folds 75

the flange 48 downwardly so as to close the flaring entrance 47 to the slot 46, as shown in Figure 10. To permit this mounting of the Venetian blind after the trim is cast it would of course be necessary to provide a comparatively small recess at the upper end of each channel, but if it is intended to cast the trim with the Venetian blind in place the flange 48 would be folded over to close the top of each channel prior to embedding the channels in the trim.

It is also a feature of the invention to provide a novel method and means for forming my pre-cast trim, it being obviously necessary to provide a special mold or molds for the purpose. Such a mold structure is shown in Figure 12 wherein I have disclosed, though it is broken away for convenience in illustration, a rectangular mold for casting the entire trim in one piece or as a unitary structure. This mold is shown as comprising a portion indicated as a whole by the numeral 58 for casting the lintel, a portion indicated as a whole by the numeral 59 for casting the sill and a pair of portions indicated as a whole by the numeral 60 for casting the sides, the portions 58 and 59 being spaced apart by the portions 60 which are connected thereto.

In detail, the lintel forming portion 58 comprises a laterally removable outer section 61 and a pair of inner sections 62 and 63 arranged in abutting engagement, the section 63 being removable by a vertical movement with respect to the section 62. The outer section 61 is formed with an inward offset 64 for defining a recess at the top of the lintel while the abutting portions of the sections 62 and 63 are offset at 65 and 66, respectively, these last mentioned offsets mating or cooperating to define the rib or ridge on the underside of the lintel. In order to provide the groove 29 defining the drip on the lintel I provide a strip 67 removably secured to the inside face of the section 63 as by screws 68.

The sill forming portion 59 comprises an outer laterally detachable section 69 and abuttingly engaged inner sections 70 and 71, the latter being detachable by an upward vertical movement. The sections 70 and 71 are provided with offsets 72 and 73, respectively, of such shape as to form the rib or ridge on the sill. The outer section 69 is formed on its inner face with a rib 74 to form the groove 28 which defines the sill drip. The side forming portions 60 which are interposed between and connect the lintel and sill forming portions 58 and 59, respectively, are of the same shape as the sill forming portion except that there is no strip 67 provided. All these portions 58, 59 and 60 are open at the top and are intended to be closed at the bottom by some appropriate means which may be adjusted, depending upon the desired width of the casting. Such a bottom closure is not shown as different expedients might be resorted to. It will be noted that the sill forming portion 59 is of greater height than the other portions as it is desirable to have the sill of the trim project outwardly beyond the sides as is customary in window construction.

This complete rectangular frame is assembled upon an appropriate supporting table or platform with whatever bottom closures are provided held in their proper positions. Concrete is then poured into the top of the various portions and will of course settle and fill the same. After the casting has set the screws 68 must be removed so that the strip 67 may move with the casting. The outer sections 64 and 69 of the

lintel and sill portions or forms are detached and moved outwardly and the sections 62 and 71 of the lintel and sill portions or forms are moved upwardly. It will be apparent that all of the sections are consequently movable relatively to the cast trim, this withdrawal being facilitated by the inclination of the inner faces of the sections 62 and 63 of the lintel portion or form, corresponding to the taper or inclination of the surfaces 22 and 23 of the lintel, and also the inclination of the inner faces of the sections 70 and 71 of the sill portion or form, these latter corresponding to the inclined surfaces 26 and 27 of the sill as previously described. It is of course to be understood that prior to the pouring of the concrete the reinforcing rods 34, the wire screen 35, the guide channels 44 and the anchor members 49 must be placed in position to be embedded. From an inspection of the drawings it is believed that the construction and operation of this mold structure will be quite clear to those acquainted with the concrete casting art.

Assuming that the trim has been pre-cast with the rods 34, wire screen 35, the metallic members 36 and the guide channels 44, as well as the anchor members 49 embedded therein, it will be understood that in the case of a solid poured wall it is simply placed in position upon the wall which has been brought to the desired height and is held by some temporary means, after which pouring of the wall is continued, the concrete entering the recesses 18 in the lintel and the corresponding recesses in the sides, as clearly indicated in Figures 2, 3, 6, 7 and 8, thereby forming a lock or bond which will positively hold the trim in place. In the case of a wall constructed of hollow blocks, as shown in Figure 5, the necessary window opening must be left for the reception of the trim and positive securing is effected by pouring the locking mass of concrete into the spaces between the recesses in the outer faces of the sides and the recesses or hollows at the ends of the blocks at the window openings, as shown at 19 in Figure 5. The trim having been secured in position, the metal frame defined by the bars 38 is placed in position and secured by means of the screws 40, it being understood that the packing 39 is placed in position at such time. The frame is then ready for the reception of the sash defined by the bars 41, the sash or sashes being hinged at the top or either side, as preferred. The stucco 31 is afterwards applied to the wall as is also the finishing material 32. This completes the structure.

From the foregoing description and a study of the drawings it will be apparent that I have thus provided a very simply and inexpensively constructed pre-cast window trim having associated therewith a metallic window frame and sashes. The arrangement is such as to be weatherproof in that the various joints are well protected. Adequate means has been provided for locking the trim into place with respect to the building wall and another feature is the inability of an intruder to obtain access to the securing means for the metal frame. It is thought that every advantage has been provided for and it is believed that they and the construction will be readily apparent to one skilled in the art without further explanation.

While I have shown the trim as designed for windows, it is equally adapted for doors, and it is also apparent that instead of the metal frame and sashes wooden ones could be employed if desired. I also reserve the right to make such

changes in the details of construction as will widen the field of utility and increase the adaptability of the device provided such changes constitute no departure from the spirit of the invention or the scope of the claims hereunto appended.

Having thus described the invention, I claim:

1. In a window construction designed to be furnished with Venetian blinds of the non-flapping type having guide pins projecting from the opposite ends of certain slats adapted to cooperate with guides, a monolithic concrete window frame including sides, sill and lintel, and having an inwardly extending rib all around, formed with a seating surface for a sash frame, said monolithic frame having Venetian blind pin-receiving guides imbedded therein, opening in the inner faces of opposite sides, said guides being parallel to one another and to the plane of said seating surface.
2. In a window construction designed to receive Venetian blinds of the non-flapping type having guide pins projecting from the opposite ends of certain slats adapted to cooperate with guides, a monolithic concrete window frame including sides, sill and lintel, and having an inwardly extending rib all around formed with a seating surface for a sash frame, and having Venetian blind pin-receiving guides imbedded therein, said guides comprising channel members forming exposed slots in the inner faces of opposite sides, said slots being parallel to one another and to the plane of said seating surface.

3. In a window construction designed to receive Venetian blinds of the non-flapping type having guide pins projecting from the opposite ends of certain slats adapted to cooperate with guides, a monolithic concrete window frame including sides, sill and lintel, and having an inwardly extending rib all around formed with a seating surface for a sash frame, and having Venetian blind pin-receiving guides imbedded therein opening in the inner faces of opposite sides, a metal sash frame seated against said seating surface and secured to said monolithic frame, said guides being parallel to one another and to the plane of the face of said sash.

4. In a window construction designed to receive Venetian blinds of the non-flapping type having guide pins projecting from the opposite ends of certain slats adapted to cooperate with guides, a monolithic concrete window frame including sides, sill and lintel, anchoring means imbedded in said monolithic frame for securing a metal sash frame in a definite position with respect to said monolithic frame, and Venetian blind pin-receiving guides imbedded therein, said guides comprising channel members forming exposed slots opening in the inner faces of the opposite sides, said slots being parallel to one another and so located with respect to said anchoring means as to be parallel to the plane of the face of the sash frame when the latter is secured to said anchoring means.

EVERETT GREY LIVESAY.
